UNITED STATES PATENT OFFICE.

LOUIS R. HORTON, OF PROVIDENCE, RHODE ISLAND, ASSIGNOR TO THE
J. B. & S. M. KNOWLES COMPANY, OF SAME PLACE.

DESIGN FOR A SPOON OR SIMILAR ARTICLE.

SPECIFICATION forming part of Design No. 23,494, dated July 24, 1894.

Application filed May 16, 1894. Serial No. 511,486. Term of patent 7 years.

To all whom it may concern:

Be it known that I, LOUIS R. HORTON, of Providence, in the county of Providence and State of Rhode Island, have invented and produced a new and original Design for Spoons and Similar Articles, of which the following is a specification, reference being had to the accompanying drawing, forming part thereof.

The drawing represents a spoon illustrating my new design, the bowl, which forms the leading and characteristic feature of my design, is shown in solid lines, the handle is shown in broken lines as it forms the incidental feature in the article of manufacture.

The principal features of the bowl consist in the irregular scalloped outline, the concave center and the convex scrolled ornaments at the edge portion which accentuate the scalloped outline.

In the drawing 5 indicates the handle portion of a spoon, ladle, or similar object, being of a size and shape to correspond with the size of the bowl and to the uses for which the size of the bowl is adapted.

6 designates the upper plain lip by which the bowl is joined to the handle, and 7 the concave central portion of the spoon bowl.

The general outline of the bowl is oval, consisting of a series of clustered scallops connected by wave-like curves 8-8, the clusters being each formed by two small side scallops 9 and 10 with a central scallop 11, or curve, of greater extension on the surface, the scalloped portions form the outlines of the scrolls 12, 13 and 14 having convex surfaces which extend inward on the surface of the bowl where they merge into the general contour thereof. Between the scrolls 12, 13 and 14 are concave portions 15 of the bowl forming lips which separate the scrolls, the lip at the lower end of the spoon being considerably larger than those at the sides.

What I claim is—

The design for a spoon or similar article as herein shown and described.

In witness whereof I have hereunto set my hand.

LOUIS R. HORTON.
